(57) CLAIM

The ornamental design for a land mine shield, as shown and described.

DESCRIPTION

FIG. 1 is a perspective view of a land mine shield, showing my new design;

FIG. 2 is a side view thereof;

FIG. 3 is a bottom view thereof;

FIG. 4 is a rear view thereof; and,

FIG. 5 is an enlarged section view taken along line 5—5 in FIG. 2.

The broken line showing of environment is for illustrative purposes only and forms no part of the claimed design.

1 Claim, 2 Drawing Sheets

FIG. 1.

FIG. 5.

UNITED STATES PATENT AND TRADEMARK OFFICE
CERTIFICATE OF CORRECTION

PATENT NO. : Des 440,907 S
DATED : April 24, 2001
INVENTOR(S) : De Wet
